(57) **CLAIM**

I claim the ornamental design for a barrier mounting bracket for roadway sign, as shown and described.

DESCRIPTION

FIG. 1 is a perspective view of my invention showing mainly top, front and left end features thereof;

FIG. 2 is a front view thereof, it being understood that a rear view is a mirror image thereof;

FIG. 3 is a left end view thereof, it being understood that a right end view is a mirror image thereof;

FIG. 4 is a top view thereof; and,

FIG. 5 is a bottom view thereof.

The broken lines shown in the drawings depicting components such as bracket clamping adjustment fasteners represent unclaimed subject matter and form no part of the claimed design.
